UNITED STATES PATENT OFFICE.

MARSHALL B. LLOYD, OF MENOMINEE, MICHIGAN, ASSIGNOR, BY MESNE ASSIGNMENTS, TO LEVI H. GREENWOOD AND GEORGE A. KEYWORTH, BOTH OF GARDNER, MASSACHUSETTS, AND WILLIAM E. HOLMAN, OF LEOMINSTER, MASSACHUSETTS, TRUSTEES.

METHOD OF PRODUCING REEDLIKE ARTICLES.

Application filed August 20, 1920. Serial No. 404,794.

To all whom it may concern:

Be it known that I, MARSHALL B. LLOYD, a citizen of the United States, and a resident of Menominee, county of Menominee, and 5 State of Michigan, have invented certain new and useful Improvements in Methods of Producing Reedlike Articles, of which the following is a specification.

My invention relates generally to the production of articles embodying therein a fabric of woven reed and the like and is particularly useful in practising those inventions of mine in which reed fabric and the like is produced independent of the frame 10 and thereafter applied thereto, or which is woven in a shape different from that desired in the finished article and thereafter reshaped as desired.

I find it desirable, in producing articles in this manner, to bind the edges thereof with metal strips. These strips enable free manipulation of the fabric without danger of disintegration thereof. These metallic strips also serve as a convenient means whereby 20 the fabric can be secured to the article frame, quickly, securely and by means of relatively few fastening devices. Functionally, I have found this practice to serve admirably and to produce an article of durable character. The objection to this practice, as heretofore carried out, resides largely in the fact that these metallic strips indicate that the article is one in which the fabric was applied to the frame, and in that 30 by some it is considered as detracting from the appearance of the article.

Furthermore, reed articles are usually tinted or colored and the metallic strip being entirely different in character from the fibrous nature of the reed fabric is not adapted to receive properly the same tints or color applications that are suitable for the fabric. In use, therefore, there was danger of the paint or coloring matter chipping from the metallic edge and marring 40 the appearance of the article as a whole.

It is an object of my invention to provide a method of producing reed articles whereby the desirable functional characteristics 45 of the edge bound fabric may be secured and all of the disadvantages thereof obviated.

It is also an object of my invention to provide a reed article, the edge portions of the

fabric of which are bound by binder strips, and which are so disposed as to present only 55 the reed fabric to view and hence to provide an article which can be tinted or color treated with any paints suitable for use with reed fabric and the like.

It is also an object of my invention to 60 provide a method of producing reed articles having a frame and independently woven reed fabric which in appearance shall approximate very closely reed articles in which the fabric is woven on the frame. 65

My invention consists generally in the steps, acts and stated sequence thereof, and in the article of manufacture resulting therefrom, whereby the above named objects, together with others that will appear herein-after, are attainable; and my invention will be more readily understood by reference to the accompanying drawings which illustrate what I consider, at the present time, to be 70 the preferred embodiment thereof. 75

In said drawings:

Fig. 1 is a view of a piece of reed-like fabric of a size and shape suitable for application to the side of the chair shown in Fig. 6.

Fig. 2 illustrates the fabric of Fig. 1 with 80 binder strips applied thereto.

Fig. 3 is a detailed view substantially on the line 3-3 of Fig. 2.

Fig. 4 is a view illustrating the fabric of Fig. 2 as further treated before application 85 to the article frame.

Fig. 5 is a fragmentary sectional view substantially on the line 5-5 of Fig. 4.

Fig. 6 is a perspective view of a chair to the sides of which fabric embodying my 90 invention has been applied; and

Fig. 7 is a detail sectional view, on an enlarged scale, substantially along line 7-7 of Fig. 6.

The fabric shown in the drawings is a 95 typical reed fabric embodying therein spaced stakes 2 over and under which the filler strands 3 are woven. The fabric shown in Fig. 1 is of a size and shape such as may be properly formed to the side of the rocking chair shown in Fig. 6. This chair, it should be understood is by way of illustration and not by way of limitation. Opposite end portions 4 and 5 thereof are composed only of filler strands and to the edge portions 4 100 and 5 of the fabric are secured metallic

binder strips 6 and 7 respectively. These metallic strips may be formed in various ways. For example—they may be merely of a U-shape which shape is then clamped or pressed 5 with the filler strands between the leg portions thereof. I do not deem it necessary to describe in detail the form of the metallic strips 6 and 7 since they do not in and of themselves constitute any part of the claimed 10 invention and may if desired be formed and initially applied in the manner shown and described in my former Patent No. 1,336,571 of April 13, 1920. In any event opposite edge portions of the fabric are provided with 15 metallic binder strips which, as is well shown in Fig. 3, are very firmly secured to the fabric. This is the type of bound fabric which has been heretofore utilized and when applied to the frame exposed to view the 20 metallic characteristics thereof. I have given much thought to the question of securing fabric to the frame so that the undesirable features of a metallic edge could be obviated. Happily an extremely simple and entirely 25 satisfactory solution to the whole problem occurred to me. Instead of applying the fabric to the frame as I have ordinarily done, I fold the metallic edge portions 6 and 7 backwardly upon the fabric as is 30 well shown in Figs. 4 and 5, thus providing outer edge portions 8 and 9 which disclose only the reed strands. I now apply the fabric to the frame so that the metallic strips 6 and 7 lie against the frame members 35 10 of the article as is probably best shown in Fig. 7. The brads or fastening devices 11 are preferably applied by separating two contiguous filler strands, inserting the fastening device, and then replacing the

strands over the head of the brad or other fastening device. In this manner not only is the metallic strip portion entirely hidden from view, but the fastening devices are likewise undisclosed. At the same time the 40 functions of the metallic binder strip as a means of preventing fraying of the fabric and as a means of enabling attachment to the frame by means of a relatively few fastening devices remain unimpaired. The completed article approximates in appearance 45 very closely that of articles in which the fabric is woven on the frame, and what is of great importance permits the application of any desired finish which is suitable for use with reed-like fabric. 50 55

The many advantages of the invention will be understood by those skilled in this art without further comment.

I claim:

The herein described method of producing 60 reed-like articles that consists in securing a metal binder strip to the edge of a stake and strand reed-like fabric in an enclosing relation thereto, folding the edge portion of the fabric containing the metal binder strip 65 back upon itself to dispose the binder strip wholly upon one side of the fabric, forming thereby an edge and a contiguous portion on one side that discloses only the strands of which the fabric is composed, and in securing the fabric to the frame by separating the outer filler strands, driving the fastening devices through the metallic binder strip and restoring the filler strands to initial 70 position to cover the said fastening devices. 75

In testimony whereof, I have hereunto set my hand, this 26th day of July, 1920.

MARSHALL B. LLOYD
